UNITED STATES PATENT OFFICE.

EDWIN H. BELL AND WILLIAM STEPHEN BOYCE, OF CHICAGO, ILLINOIS.

RAILWAY TIE.

Application filed November 23, 1927. Serial No. 235,264.

This invention relates to railway track devices and more particularly to a railway tie having its top surface initially formed or shaped to be complementary to the shape of the tie plates intended to be seated thereon, or pre-shaped to receive only certain portions of plates whose bottom surfaces are designed to co-operate with the preshaped tie to effect comparatively speedy and efficient ultimate seating.

The object of the invention is to secure initially correct and prompt seating of the plate on the tie and compression of tie fibres adjacent the preshaped areas, and to avoid breaking down of fibres of the wooden tie and consequent deterioration thereof.

The objects and advantages of the invention will be more fully understood as we proceed to point out the disadvantages attending the use of railway ties having flat top surfaces for metallic tie plates to rest upon, and the resultant irregular, improper and delayed seating of said tie plates.

When a railroad track is being laid according to present methods, tie plates, preferably provided with depending ribs or undulating surfaces for engaging the tie, are placed on top of the flat tie in position to receive the rail, and both rail and tie plate are secured to the tie by means of spikes of conventional type. Train-loads passing over the rails are relied upon to cause those parts or projections lying in a plane below the ultimate bearing surface of the plate to gradually enter the tie and produce ultimate seating of the plate thereon.

The time and load required to produce complete seating of plates on flat top ties is varied according to the class of timber used for the ties. Obviously the seating in so-called hard wood ties is somewhat retarded, particularly if projections on the tie plate bottom are at right angles to the grain of the timber. In ties of softer wood the seating is relatively rapid. The mixing of hard and soft wood ties in the average track construction is a common practice and the resultant variation in time of seating of plates naturally produces irregularities of the rail surface, which greatly affect the smoothness or riding quality of the track. Knots and hard spots in the wood ties also contribute to the non-uniformity.

Another disadvantage growing out of present methods is that the slow seating of

tie plates on hard wood ties permits gravel, dirt and other foreign matter to accumulate between the tie plate bottom and the surface of the tie in the meantime and often makes the final and uniform seating of the plate impossible.

Seating in improper position is also attributable to the following conditions: In the transmission of axle load to rail through a standard coned wheel, the angular application of load on the rail results in horizontal as well as vertical thrust. The effect of the horizontal thrust is intensified while tie plate seating is taking place and when the plates are improperly and non-uniformly seated. The horizontal load or so-called thrust transmitted from rail base to abutting shoulder of tie plate under these conditions causes the plate to ultimately become seated out of alignment or in a position producing widening of the gauge of the track. Variations between the sizes of punched spike holes and of the ordinary track spike, often permit the spiking of tie plates in an angular relation to the rail base so that the plates become seated under influence of horizontal thrust in a position wherein the rail abutting shoulder is not parallel to the rail flange. Plates carelessly applied, especially to ties which are low or in soft spots in track, frequently result in the transmission of loads to thin portions of the rail base and produce fractures in the rail flanges.

All these objections are attributable to slow, non-uniform and improper seating of plates on ties. The correction of these conditions is an item of great expense in maintenance of track as it entails the removal of spikes, readjustment of tie plates and respiking to correct gauge positions between rail heads. The damage resulting from projections on improperly seated tie plates to the tie fibres and from replacing spikes is obvious.

While it is well known that ultimate penetration of the tie by transversely extending projections on the tie plate bottom will resist horizontal thrust and maintain a plate in position when once properly seated, it is obvious from what has been stated that by present methods a certain time is required before seating is accomplished on the flat top tie, and in the meantime there is abundant opportunity for disarrangement of the plate position relative to the rail flange and

consequent improper seating, and for the accumulation of foreign matter which may prevent any ultimate seating; also, that plate projections which are deep and sharp will cut and injure the fibres of the tie, and cause decay.

The tie plate constructions shown in Boyce Letters-Patent Reissue No. 15,989, and Nos. 1,583,773, 1,583,774 and 1,587,751, were especially designed to become efficiently and quickly seated without injurious penetration of the surface of flat top ties. Relatively narrow, initial bearing surfaces and rounded tie engaging ribs were provided, with the results that loads were concentrated, initially, on these narrow bearing surfaces, and relatively prompt and correct seating on flat top ties secured without the usual cutting of fibres. The present invention, while contemplating the provision of ties having top surfaces complementary to any bottom design of plate, is also particularly productive of beneficial results when embodied in ties having top surfaces complementary to, or grooved or shaped to receive only certain depending portions of plates such as those above referred to, having relatively narrow, initial bearing surfaces through which load is immediately transmitted to those parts of the tie adjacent the grooved or preshaped portions and compression and seating effected.

The advantages of the invention are manifest: the preshaping or grooving insures the correct positioning of the plate on the tie, the depending portions being received in their intended seats; the initial bearing surfaces of the plate thereupon in contact with the tie at once receive and transmit axle loads to the tie surfaces subjacent the initial bearing surface of the plate, and compress the said tie while maintaining the intended position of the plate thereon. No undue cutting or breaking down of tie fibres, or disarrangement of plate position, with respect to the rail flanges, are possible. The compression of the tie beneath the initial bearing surfaces, and adjacent the preshaped areas, furnishes a protective veneer to those portions of the tie which have heretofore been subject to deterioration.

The method of shaping or configurating the top surface of the tie is immaterial and may be varied as desired. It may be accomplished by branding, steaming, pressing, cutting or molding the materials of that portion of the tie intended to receive the plate.

In the drawings:

Figure 1 is a perspective view of a part of a tie embodying our invention, initially complementary to the tie plate seated thereon.

Figure 2 is a view similar to Figure 1 with the plate removed from the tie.

Figure 3 is a longitudinal, vertical, sectional view of a modified form of tie em-

bodying our invention, and showing in superposed but spaced apart relation, a tie plate such as shown in Figure 1 intended to be seated thereon.

Figure 4 is an enlarged sectional view showing one end of the tie of Figure 3, with the tie plate in initial position thereon.

Figure 5 is a duplication of the parts of Figure 4, but showing the plate ultimately seated on the tie.

Figure 6 is a vertical, longitudinal, sectional view of a portion if a tie embodying our invention, the same being initially complementary to the under surface of the modified form of plate shown in section in superposed, spaced apart relation to the tie.

Figure 7 is a view similar to Figure 3, showing the modified form of tie, and in spaced, superposed relation, a plate such as shown in Figure 6, intended to be seated thereon.

Figure 8 is an enlarged sectional view showing one end of the tie Figure 7, with the tie plate in initial position thereon.

Figure 9 is a duplication of the parts of Figure 8 but showing the plate ultimately seated on the tie.

Figure 10 is a perspective view of a portion of a tie embodying another modification of the invention.

Figure 11 is a transverse, vertical, sectional view taken in the plane of the line 11-11, of Figure 10, looking in the direction indicated by the arrows and showing in superposed but spaced apart relation a section of a tie plate intended to be seated thereon.

Figure 12 is a longitudinal, sectional view of a tie embodying our invention with still another type of plate seated thereon.

Referring now to that embodiment of our invention shown in Figures 1 and 2, A indicates a tie initially formed to be complementary to the tie plate B intended to be seated thereon. It will, of course, be understood that each tie is adapted to receive two of said tie plates, one near each end, properly spaced apart to conform to the width of the track.

The plate B shown is provided at its top with the usual rail bearing surfaces 15, rail abutting shoulder 16 and spike holes 17. Its bottom surface is provided with a central, median, transverse groove or recess 18, and with end recesses 19, 19. Intermediate the end recesses 19 and median portion 18, and extending transversely of the plate, are downwardly projecting portions 20, each provided with a rounded depending rib 21.

It is common practice to run ties through a planer to prepare level surfaces for the reception of tie plates. The preshaping about to be described may be accomplished in the same operation.

The tie A is shaped and configurated near each end to have its top surface correspond to the bottom surface of the tie plate B. On

each side of the surface 22, which extends across the tie, is a transversely extending groove or recess 23 and the surface of each groove 23 is provided with a groove or recess 24. At one side of each of the grooves 23 is a surface 25 in substantially the same plane as the surface 22.

It will be understood that the plate B will be placed upon the tie A so that the parts 20 with depending ribs 21 will enter the grooves 23 and depressions 24, respectively, and the median transverse surface 18 of the plate will be supported by the tie surface 22.

If desired, the tie may also be provided with holes adapted to register with the spike holes 17 to facilitate the placing of spikes through the plate and into the tie.

In this form, the tie is initially complementary to the plate intended to be used thereon.

Referring now to Figures 3, 4 and 5, it will be seen that the plate B heretofore described is shown in combination with a modified form of tie indicated at C. The tie C is not initially complementary to the plate B but is preshaped to receive only certain portions of the plate bottom. The flat top surface 26 of the tie C is grooved transversely at 27, the grooves being spaced apart so as to register with and be adapted to receive the ribs 21 of the plate B. The grooves are preferably of slightly less depth than the aggregate depth of the bearing members 20 and ribs 21; that is, the distance from the tip of 35 the rib 21 to the plane of the bearing surface 18 is slightly greater than the depth of the groove 27.

As shown in Figure 4, the plate is placed so that the transverse rib 21 is received in the 40 groove 27 and the initially bearing surfaces 20, 20, rest upon the surfaces 28 of the tie subjacent the bearing surface 20. Loads transmitted through the rail to the plate B are concentrated on these bearing surfaces 20 and transmitted to the parts 28 of the tie 45 and promptly cause the parts 20 and 21 to assume the position shown in Figure 5, completely filling the groove 27 and depressing the wood fibres as indicated by the shading at 29.

In Figure 6, we have shown a tie D, which is initially complementary to the under surface of the plate E. The plate E is provided with median and end bearing surfaces 55 30 separated by thickened portions 31 provided with ribs 32. The plate E is adapted to immediately become seated in the complementary shaped top surface of the tie D, as has already been explained with respect to 60 the plate B on tie A.

In Figures 7, 8 and 9, we have shown this same plate E in connection with the modified form of tie indicated at C in Figures 3, 4 and 5. That is to say, the tie is preshaped 65 to receive the ribs 32 of plate E and to func-

tion with respect to the ultimate seating in the manner heretofore described with reference to plate B in Figures 3, 4 and 5.

Referring to Figures 10 and 11, the tie F is similar to the tie A heretofore described 70 in that it is provided with surfaces which have been designated by the numbers applied to similar parts on tie A, with the exception of the transverse median surface. In the form now being described, the median portion of the tie F between the surfaces 23 is provided with an undulating surface 33 which is complementary to the "compression bottom" form of plate indicated at G. It will be understood that the bottom 75 surface of plate G is complementary to the seat in tie F, and that the series of arcuate depressions 34 of the plate G will be seated in the corresponding surface 33 of the tie F.

In Figure 12, a flat bottomed plate H provided with ribs is seated in a preshaped tie 80 C, such as heretofore described.

It will be understood that the various forms herein shown are merely illustrative of ties adapted to receive certain types of 90 tie plates. Numerous other examples might be shown.

Obviously modifications may be made without departing from the scope of our invention, and we do not intend to be limited 95 to the particular forms shown and described, except as set forth in the appended claims.

We claim as our invention:

1. A non-metallic railway tie adapted to center and accelerate seating of a tie plate 100 having its top surface initially cut and shaped to receive depending portions of the bottom of the tie plate to be seated therein under pressure.

2. A non-metallic railway tie adapted to 105 center and accelerate seating of a tie plate therein under pressure, the top surface of which is provided with transverse grooves adapted to register with ribs on the bottom surface of the tie plate to be seated thereon.

3. The combination of a railway tie and a tie plate, the latter having spaced apart, relatively narrow initial bearing surfaces between its ends, transversely of the bottom of said plate, and ribs depending from said initial bearing surfaces, said tie being preshaped to receive said depending ribs and to be compressed adjacent said preshaped parts by the transmission of load through the initial bearing surfaces of the plate on 115 the tie.

4. The combination of a railway tie and a tie plate, the latter having bottom surfaces extending transversely of the plate, in different planes, said tie being preshaped to receive certain of said bottom surfaces and adapted to be compressed by transmission of loads through said other surfaces to effect ultimate seating of the plate on the tie. 125

5. As a new article of manufacture, a non-metallic railway tie having its top surface initially shaped to be complementary to the shape of the bottom of the tie plate to be seated thereon.

6. As a new article of manufacture, a non-metallic railway tie having its top surface initially molded or pressed to form a tie plate seat therein.

10 7. As a new article of manufacture, a non-metallic railway tie provided in its top with a plurality of transversely extending surfaces in different planes to provide a tie plate seat in the tie.

15 8. As a new article of manufacture, a non-

metallic railway tie provided in its top with a plurality of transversely extending surfaces in different planes to provide a tie plate seat in the tie, said surfaces being below the top of the body of the tie.

9. A non-metallic railway tie adapted to center and accelerate seating of tie plates having its top surface preformed to receive depending portions of tie plates to be seated therein under pressure.

In testimony, that we claim the foregoing as our invention we affix our signatures, this 21st day of November, 1927.

EDWIN H. BELL.

WILLIAM STEPHEN BOYCE.
